UNITED STATES PATENT OFFICE.

HIPPOLYTE W. ROMANOFF, OF LEVALLOIS-PERRET, FRANCE.

FILING, SAWING, AND GRINDING MACHINE.

Application filed November 2, 1926, Serial No. 145,845, and in France May 14, 1926. Renewed January 17, 1928.

The present invention relates to a filing, sawing and grinding machine principally characterized by the fact that when it is employed as a filing machine, the tool, which in this case consists of a round or rat's-tail file, may receive simultaneously a vertical alternating movement and a continuous rotary movement. Under these conditions the file works with its entire surface, thus augmenting the efficiency of the tool.

10 The drives for the alternating vertical movement and for the rotation of the tool, although effected by the same motor or depending upon the same transmission shaft, are independent, that is to say, it is possible to give the tool either an alternating movement only or a rotating movement only.

This independence of the drives enables the machine forming the subject-matter of 20 the invention to be applied not only as a filing machine but also as a sawing machine, when it impresses upon the tool only an alternating vertical movement, and as a grinding and piercing machine, when it gives 25 the spindle only a rotary movement.

In the drawings accompanying the present specification:

Fig. 1 is an elevation and profile view of 30 the machine forming the subject-matter of the present invention;

Fig. 2 is a front elevation of the machine;

Fig. 3 is a perspective view with parts in section and parts removed from the shafts, of the mechanism controlling the rotary movement;

Fig. 4 shows on a larger scale partly in section and partly in elevation, the device controlling the alternating movement;

Fig. 5 is a front view of the same device;

Fig. 6 shows in plan the mounting of a 40 piece of work on the plate of the filing machine, the said piece being machined for a semicircular profile;

Fig. 7 is a plan view of the plate, upon 45 which is mounted a piece of work to be cut into a spur gear wheel;

Fig. 8 shows in plan the mounting of a piece of work on the plate of the filing machine, this piece being machined to present 50 a rectilinear face.

As can be seen in Figures 1 and 2, the machine is moved by an electric motor 1 usually fixed to the base of the frame, but it may alternatively receive its movement from an 55 adjacent transmission shaft.

The frame that supports the various members consists of a base 2, into which is fixed a cylindrical column 3, along which can slide the sleeves of the plate and of the clamping chuck.

Upon the column 3 is fixed the bracket 4, which supports the various members concerned in the rotary drive.

The form and general construction of this frame, as just described and as illustrated in 65 the accompanying drawings merely constitute one example of the construction of the support of the various members of the machine and it will be understood that this support may be given quite a different form 70 and general construction without the characteristics of the invention, which are all contained in the devices which are about to be described, being in any way affected thereby.

75 The driving device for rotating the spindle carrying the tool is constructed in the following manner, as illustrated in Figures 1, 2 and 3.

A pulley 5 keyed on to the motor shaft 80 transmits the movement from the latter to a pulley 6 which rotates integrally with the spindle 7, upon which the tool 53 is mounted. This transmission is effected through the medium of a belt 8 which passes over guide 85 pulleys 9, 10, the position of which is adjustable by displacing their shaft 11 along a guide 12, these pulleys 9 and 10 admitting moreover of being fixed in the selected position by tightening a screw controlled by the 90 handle 13.

The ratios between the pulleys 5 and 6 are judiciously selected so that the spindle may receive a rotary movement corresponding to the work to be effected or to the nature of 95 the metal to be worked. With this end in view the extremity of the spindle can receive stepped pulleys such as 6, 6' and in this way the desired speed can be obtained by merely changing the pulley 6.

The spindle 7 rotates in smooth bearings 14 and 15 which ensure its longitudinal rigidity.

This rotational driving device is therefore extremely simple and it will be understood that it could be constructed in some other way as regards the transmission members according to the position of the motor or of the transmission shaft.

The device that gives the tool an alternat-

ing vertical movement is the following (Figures 1, 2, 4 and 5).

The base 2 carries a sleeve 54 either cast on to it or fixed on to it by any suitable means. This sleeve serves as a bearing for a shaft 55, on to which is keyed a pulley 16, which can receive a rotary movement from a pulley 17 fast to the motor shaft through the medium of a belt 18.

To the other extremity of the shaft 55 is keyed a chain pinion 19 which drives an endless chain 20 which elsewhere engages with a pinion 21 loose on a trunnion 22, the position of which is adjustable in a slot 23 concentric with the axis of the trunnion and cut in a shoulder 24 of the sleeve 54.

To one of the pins 25 of the links of the chain 19 is jointed a member 26 carrying a tapped socket 27 into which can be screwed a rod 28, the position of which can be fixed by a nut 29.

It will be understood that when the shaft 55 rotates, the member 26, jointed to the pin 25, follows the movements of the chain and transmits to the rod 28, with which it is virtually integral, an alternating movement.

The other extremity of the rod 28 has a cap 29' which is pivoted to a ring 30, virtually integral with a screw-threaded rod 31.

The latter engages in a hole in the U-shaped member 32, the two extremities 33 and 34 of which are bored out along a suitable diameter in order to fit over the spindle 7, bearing at the same time upon the shoulders 35 and 36 carried by the spindle.

The position of the screw-threaded rod 31 in the member 32 can be adjusted and fixed by means of nuts such as 37 and 37'.

The screw and nut device 29 which is carried by the rod 28 on the one hand, and the screw-threaded rod 31 on the other hand therefore enable the length of the rod to be adjusted, and, consequently, the position of the fork 33, 34 on the spindle, which amounts to adjusting the ends of the travel of the tool.

Finally, the member 32 is constantly urged upwards by a spring 38 attached by one of its ends to a hook 39 virtually integral with the member and by its other end to a hook 40 prolonged by a screw-threaded rod 41 the position of which can be varied upon a bracket 42, which is itself movable in a sleeve 43 integral or virtually integral with the frame.

The alternating vertical movement of the member 32 is controlled by that of the rod 28, and its stroke is equal to the distance which in vertical projection separates the extreme positions of the pivot 25. In this alternating movement the member 32 drives the spindle 7, without opposing the rotation of the latter, by the fork formed by its extremities 33 and 34.

The tool therefore receives, in conjunc-

tion with a continuous rotary movement, an alternating vertical movement, this latter having a certain flexibility in consequence of its chain drive and the action of the spring 38.

The adjustment of the angular velocity of the tool is effected either by varying the speed of the motor or of the transmission shaft or else by judicious selection of the pulleys that rotate fast to the spindle.

The adjustment of the speed of the alternating movement may also be effected by the motor or by changing the pulleys; the determination of the ends of its travel by the length of the connecting rod 28 and the adjustment of the amplitude of the movement by displacement of the pinion 21 in the slot 23.

The machine as just described enables pieces of work to be machined by filing along various outlines, the entire surface of the round file being utilized.

By way of example Figures 6, 7 and 8 of the drawings illustrate the mounting upon the plate of the machine, of pieces of work to be machined along various profiles.

In Figure 6 is shown a piece of work 44, the extremity of which it is desired to file along a semicircular curve.

The piece of work is pivoted to the plate by a pivot 45 integral or virtually integral with the clamping chuck 46, the position of which is maintained fixed by any suitable means, such for example as the hook 47 shown in the figure.

The extremity of the piece of work 44 after being roughly shaped is presented to the file by one of its sides in such a manner that the distance from the axis 45 to the moving periphery of the tool is equal to the semicircular radius of the curvature of the piece of work, and the workman limits himself to rotating the piece as the work progresses.

Figure 7 illustrates the work of filing the extremity of the teeth of a spur pinion 48, the piece of work being successively pivoted to the plate on the axes 49 and 49' of the arcs of circles along which the teeth are cut.

Finally Figure 8 shows under treatment a piece of work 50, the face 51 of which is to be straightened, the said piece being guided by an angle-iron 52 fixed to the plate and being pushed forward as the work progresses.

It is easy to understand that by applying these various devices and following previously prepared templates it will always be possible with the machine to file pieces of work to any outlines, the movements to be given in the course of the work to the pieces to be machined admitting moreover of being given either by hand or by any suitable automatic arrangement.

If the belt 8 is removed or shifted on to a

pulley turning loosely upon the spindle, the rotary movement is suppressed and only the alternating movement of the tool remains.

It is thus possible to utilize flat files for 5 certain work or to employ the device as a sawing machine.

If, on the contrary, the alternating movement is stopped, the machine can function as a drilling or boring machine or as a 10 grinding machine, the descending movements of the spindle admitting of being attained by any suitable means.

The machine which has been described above and which is illustrated in the accompanying drawings only constitutes one constructional form of the invention which is more particularly characterized by the combination of the alternating and rotational movements, the operation of which has been 20 explained.

It is quite understood that the shapes of the various members, and also their relative positions on the frame, may be different from those shown in the drawings and that 25 in particular a filing machine can be constructed in which the drives of the alternating and rotational movements would be located at the lower part of the machine under the plate without thereby departing 30 from the characteristics of the invention.

What I claim is:

1. A filing, sawing and grinding machine, comprising a tool, a tool holding spindle, means for imparting a positive rotational drive to said tool holding spindle, said spindle remaining longitudinally displaceable, 35 and an endless chain, a motor controlling the movement of said endless chain, a fork for determining the vertical displacement of

the tool holding spindle, a connecting rod 40 jointed at one end to the endless chain and at the other end to said fork, and means for adjusting the positions of the ends of the strokes of the tool and the amplitude of its vertical movement. 45

2. A filing, sawing and grinding machine, comprising a tool, a tool holding spindle, means for imparting a positive rotational drive to said tool holding spindle, said spindle remaining longitudinally displaceable, 50 an endless chain, a motor controlling the movement of said endless chain, a fork for determining the vertical displacement of the tool holding spindle, a connecting rod, a flexible joint between one end of said connecting rod and the endless chain, and an opposing spring connecting the other end of said connecting rod to the fork.

3. A filing, sawing and grinding machine, comprising a tool, a tool holding spindle, 60 means for imparting a positive rotational drive to said tool holding spindle, said spindle remaining longitudinally displaceable, an endless chain, a motor controlling the movement of said endless chain, a fork for 65 determining the vertical displacement of the tool holding spindle, a connecting rod, a flexible joint between one end of said connecting rod and the endless chain, an opposing spring connecting the other end of said 70 connecting rod to the fork, and means for adjusting the positions of the ends of the strokes of the tool and the amplitude of its vertical movement.

In testimony whereof I have signed my 75 name to this specification.

HIPPOLYTE W. ROMANOFF.
